UNITED STATES PATENT OFFICE

EDWIN MALCOLM PAYNE, OF SOUTHALL, ENGLAND, ASSIGNOR, BY MESNE ASSIGNMENTS, TO RADIO CORPORATION OF AMERICA, OF NEW YORK, N. Y., A CORPORATION OF DELAWARE

ELECTROMAGNETIC VIBRATORY DEVICE

Application filed February 16, 1929, Serial No. 340,569, and in Great Britain March 21, 1928.

The present invention relates to electromagnetic vibratory devices, such for example as telephone reproducers or devices for recording sound or for reproducing recorded sound, in which an armature of magnetic material is adapted to vibrate towards and away from one or more magnetic poles.

According to the present invention an electro-magnetic device comprises an armature mounted for vibration towards and away from a magnet pole wherein the surface of the armature adjacent the magnet pole is other than flat, the co-operating surface of the magnet pole being shaped to correspond. In this way the stiffness/mass ratio of the armature can be greatly increased without loss of electro-magnetic efficiency.

The invention is illustrated in the accompanying drawings as applied to a device for converting a sound trace upon a disc record into corresponding electrical oscillations.

Figs. 1 and 2 are views in plan and elevation respectively of an armature in accordance with the invention and

Figs. 3 and 4 are similar views of a magnet system in accordance with the invention.

The magnet system comprises two U-shaped permanent magnets 1 and 2 arranged with their poles 3, 3' and 4, 4' respectively pointing inwards and with the North pole of one opposite the South pole of the other.

The armature comprises a boss 5 provided with pivot holes 6 with the aid of which the armature is pivotally mounted on the magnet system. The axis of vibration of the armature is indicated in Figs. 1, 2 and 4 by the reference 7. The armature may be shaped in such a manner as to increase its inherent rigidity or stiffness to internal vibration without substantially increasing its mass, preferably by means of corrugations or ribs extending in a direction to stiffen the armature against internal vibration. In the form shown, working blade 8 of the armature is ribbed or corrugated in a direction perpendicular to the axis 7. Suitable means may be provided for clamping a reproducing stylus in the projecting member 9. The working surfaces of the two magnet poles 3, 4 are shaped to correspond with the corruga-

tions upon the armature blade 8, thereby preventing loss of electromagnetic efficiency. The shaping of the pole surfaces may be carried out with a suitably shaped milling cutter.

As shown in Fig. 4 damping pads 10 of rubber or other suitable material may if desired be arranged upon suitable brackets 11 carried upon the upper side of the upper poles 3 and 4 and bear upon the two sides of an extension of the armature blade 8. The corrugations may be continued along this extension and a greater damping surface is then offered than if the extension piece were flat.

A suitable coil (not shown) is arranged around the armature blade 8 and vibrations of the armature blade 8 generate electro-motive forces in this coil in known manner.

In the arrangement described the armature blade is of constant thickness but the invention is not limited to such an arrangement.

I claim:

1. An electromagnetic vibratory device comprising a magnet, and an armature mounted for vibration and cooperating therewith, said armature being provided with stiffening corrugations to prevent internal vibrations thereof and the pole face of said magnet being shaped to correspond with the corrugated surface of the armature.

2. An electromagnetic vibratory device comprising a magnet, and an armature mounted to vibrate to cooperate with said magnet, said armature being provided with stiffening corrugations extending in the direction of propagation of internal vibrations in said armature, and the pole face of said magnet being shaped to correspond with the corrugated surface of said armature.

3. An electromagnetic vibratory device comprising a magnet and a vibrating armature pivotally mounted to cooperate therewith, said armature being provided with stiffening corrugations extending perpendicular to the pivotal axis thereof and the pole face of said magnet being shaped to correspond with the corrugated surface of the armature.

4. In a device of the class described, the combination of a corrugated armature of

substantially constant thickness, the corrugations extending in a direction to impart stiffness against internal vibration, and a cooperating magnet having a pole face shaped to correspond with said corrugations.

5. In a device of the class described, the combination of a pivoted armature of substantially constant thickness and having corrugations extending at right angles to the 10 pivotal axis thereof, and a magnet having a pole face shaped to correspond with the corrugated surface of said armature.

6. In a device of the class described, the combination of a vibrating armature having 15 corrugations extending in a direction to impart stiffness against internal vibration, a cooperating magnet having a pole face shaped to correspond with said corrugations, and damping means engaging the corrugated 20 surface of said armature.

7. In a device of the class described, the combination of a vibrating armature pivotally mounted and provided with stiffening corrugations extending perpendicular to the pivotal axis thereof, a magnet cooperating with 25 said armature and having a pole face shaped to correspond with the corrugated surface of the armature, and damping means engaging the corrugated surface of the armature.

30. 8. An electro-magnetic vibratory device comprising a magnet and an armature mounted for vibration about an axis toward and away from a pole of said magnet, the cross-sectional form of said armature in a plane 35 parallel to said axis being non-rectangular, whereby the surface opposed to the magnet pole is non-planar, and the said pole being shaped to correspond to said surface.

In testimony whereof I have signed my
40 name to this specification.

EDWIN MALCOLM PAYNE.
